ATTORNEY.

UNITED STATES PATENT OFFICE.

EDWARD MARKELL, OF BALTIMORE, MARYLAND.

HOUSE-DOOR LETTER-BOX.

SPECIFICATION forming part of Letters Patent No. 449,372, dated March 31, 1891.

Application filed January 22, 1891. Serial No. 378,646. (No model.)

To all whom it may concern:

Be it known that I, EDWARD MARKELL, a citizen of the United States, residing at Baltimore city, in the State of Maryland, have invented certain new and useful Improvements in Letter-Boxes, of which the following is a specification.

This invention relates to letter-boxes for residences, &c., and this application is a companion one to that filed by me December 11, 1890, Serial No. 374,310.

The object of my present invention is to so pivot the swinging gate or flapper in the receiving-slot that it requires no spring to close, but acts by its own weight, and when closed its outer surface is flush with that of the front of the box or the door through which the receiving-slot is made.

With these ends in view the invention consists in certain peculiarities of construction and combinations of parts described herein-after, and pointed out in the claims.

In the accompanying drawings, illustrating the invention, Figure 1 represents an outside view of a portion of a street-door to which the box is applied; Fig. 2, a vertical cross-section of the box; Fig. 3, a detail view showing the swinging gate or flapper and the hanger-plate in which the same is pivoted; Fig. 4, a detail of a guard-plate which is located in the box; Fig. 6, a vertical section of a modified form of the box, and Fig. 5, a front elevation of the lower half of the latter.

In the drawings the box is shown secured to the street-door of a residence, and the letter A designates the door, and B the box, which is secured to the inside of the same. The door A thus constitutes the front of the box, and through it is made a rectangular opening or receiving-slot a, with a beveled lower side a'.

The box B is of substantially the same form and construction as that shown in my companion application above referred to, and its bottom is closed by a hinged lid b³, having a suitable lock.

A swinging gate or flapper b is pivotally suspended in the opening a from a hanger-plate c, which is secured to the outside of the door A and extends across the upper portion of the said opening. The said flapper is pro-

vided with trunnions b', which project from its opposite ends, and the hanger-plate is formed with boxes c' at its ends, which fit up against the door A, and in which said trunnions are journaled. The said hanger-plate, between the boxes c', is recessed or chambered, as at d, to accommodate the upper portion b² of the flapper b, which is between the trunnions, and fits beneath the said plate and gives room for the flapper to swing back into the box. The said top portion b² and trunnions project forward of the plane of the front face of the flapper. The flapper b swings inward, and its lower edge e is beveled to coincide with the beveled lower side a' of the receiving-slot a and abuts against the same, whereby the said beveled side a' stops the flapper in its forward movement and holds it flush with the outside face of the door A, and the center of gravity of the flapper being in front of the latter it will be kept in contact with the said beveled surface a' by its own weight. It will be observed that, owing to the pivots of the flapper being located forward of the outside face of the door A, the center of gravity of said flapper is correspondingly in front of the door, and if the flapper were free to swing forward it would naturally fall to a position where it would project from the door. It will be observed that the flapper as thus hung is pivoted on the outside of the door A and that its pivots are concealed and protected by the hanger-plate c. It will also be apparent that the said flapper closes and maintains its closed position by its own weight and requires no spring.

The number of the residence and the name of the occupant can be inscribed in suitable manner on the front face of the flapper, which thus serves as a door-plate, and also the word "Letters" or some equivalent to indicate that mail is to be deposited through it.

Inside the box B a guard-plate w, having prongs w², is pivoted below the opening a and held in an inclined position by a prop w'. It will be seen that this guard-plate will act to prevent the withdrawal of matter from the box through the receiving-slot.

In Figs. 5 and 6 a modified form of box is shown, which is adapted for use as a collec-

tion-box, and in which the receiving-slot *a* is made in the top and closed by a hinged lid *b*, having a curved arm *m*, projecting from its back and provided with a weight *n* on its 5 end, which weight is back of the pivotal point of the lid, and thus acts by gravity to close the latter. Back of the lower open portion *B* of the box a printed card *o*, having hours of collection, is placed with a glass *o'* in front 10 of it.

Having thus described my invention, what I claim as new, and desire to secure by Letters Patent, is—

1. A letter-box having a receiving-slot in one side provided with a beveled lower side, 15 and a swinging flapper pivoted in said slot and adapted to open back into the box and provided with a beveled lower edge which coincides with the beveled lower side of the 20 said receiving-slot and is adapted to abut against the same, the pivot of said swinging flapper being located in front of the outside surface of the side of the box in which the receiving-slot is made, for the purpose specified.

2. A letter-box having a receiving-slot in one side provided with a beveled lower side, 25 and a swinging flapper pivoted in said slot and adapted to open back into the box and provided with a beveled lower edge which coincides with the beveled lower side of the 30

said receiving-slot and is adapted to abut against the same, the pivot of said flapper being located in front of the outside surface of the side of the box in which the receiving-slot is made and also in front of the 35 face of the flapper, whereby when the latter is closed its front surface is flush with that of the said box side which has the receiving-slot.

3. The combination of the door *A*, having 40 a receiving-slot with a beveled lower side, a box *B*, secured to said door, a swinging flapper hung in said slot and opening back into the said box and having suitable trunnions projecting from its opposite ends and a beveled lower edge which abuts against the said beveled lower side of the receiving-slot in the door, and a hanger-plate secured on the outside of the said door and extending across the upper portion of the slot in the latter and 45 having boxes at its opposite ends in which the trunnions of the flapper are journaled, the said hanger-plate covering the upper portion of said flapper.

In testimony whereof I affix my signature in 50 the presence of two witnesses.

EDWARD MARKELL.
